UNITED STATES PATENT OFFICE.

EUGENE F. TRENT, OF JERSEY CITY, NEW JERSEY.

LAMP.

SPECIFICATION forming part of Letters Patent No. 519,852, dated May 15, 1894.

Application filed August 4, 1890. Serial No. 360,938. (No model.)

To all whom it may concern:

Be it known that I, EUGENE F. TRENT, of Jersey City, Hudson county, and State of New Jersey, have invented a certain new and useful Improvement in Lamps, of which the following is a specification.

I will describe a lamp embodying my improvement and then point out the novel features in the claims.

10 In the accompanying drawings, Figure 1 is a central vertical section of a lamp embodying my improvement. Fig. 2 is a perspective interior view of a portion of the reservoir and appurtenances thereof. Fig. 3 is a horizontal section taken at the plane of the dotted line $\alpha\alpha$ Fig. 1. Fig. 4 is an enlarged vertical section of the upper portion of the reservoir and certain parts of the burner. Fig. 5 is a side view of a tube provided with spirals for effecting the adjustment of the wick carrier. Fig. 6 is a top view of the same and shows in dotted outline the lower portion of the outer shell of the wick tube. Fig. 7 is a sectional side view of the outer shell of the wick tube. Fig. 8 is a top view of a deflector. Fig. 9 is a transverse vertical section of the deflector. Fig. 10 is a perspective view of a pair of clamping pieces such as are used in the said deflector.

30 Similar letters of reference designate corresponding parts in all the figures.

A designates the lamp reservoir or fount. It may be of any suitable construction. As here shown, it is supported by a hollow pedestal or foot piece B having perforations near the base to admit air. In this base piece a drip cup C will preferably be arranged.

35 D' D² designate the wick tube. It is composed of two cylindric sheet metal shells arranged concentrically one within the other at such distance apart as to leave a space for the accommodation of an annular wick E. The inner shell D' is fastened in an opening formed in the bottom of the reservoir and constitutes a central draft tube, through which air entering the base piece ascends to the inner surface of the flame.

40 The outer shell D² of the wick tube is shown as made larger at the lower end than at the upper end and as having a tapering portion d intermediate of the two end portions. This construction will facilitate the upward move-

ment of the wick as it will reduce the liability of the lower edge engaging with the wick. When this shell of the wick tube is made detachable, as in the present instance, its construction also facilitates placing it, as it reduces the liability of the lower edge to engage with the wick in this operation.

45 It will be seen that the lower part of the outer shell of the wick tube is provided with an enlargement d'. This enlargement d' is in the present instance made of a separate piece of metal and it extends outwardly at an upward incline and thence downwardly. At 55 the lower portion it has an outwardly extending shoulder-like projection d² and at the lower extremity below the shoulder-like projection d² it has fastened to it a ring d³ which preferably will be made of hard rubber or other good non-conductor of heat. The downwardly extending portion of the part d' is provided with a number of radial projections d⁴ which are shouldered intermediately of their upper and lower ends. These projections 60 will preferably be struck up out of the metal forming the part d'. Their function will be explained presently.

50 F designates a wick carrier consisting of a band of sheet metal which is of a size to surround the wick E and is provided with inwardly bent teeth f for engaging the wick and with outwardly extending arms or pins f' which are arranged on the same horizontal plane and enter spiral grooves or slots in a tube 65 G. The arms or pins f', after passing through the tube G, pass into guides H shown as consisting of pairs of wires fastened in the bottom of the reservoir A and also in a collar a which is provided at the top of the reservoir. 70 These guides H preclude the wick carrier from rotating.

55 By rotating the tube G the wick carrier F may be elevated or lowered for the purpose of adjusting the tip of the wick.

60 The collar a of the reservoir A is turned or bent inwardly from a cylindric portion a' of the reservoir and it is provided with notches a² between the guides H of each pair. Provision is thus afforded for removing the wick carrier from the reservoir. Preferably the collar a will incline downwardly toward its inner circumference and be provided at the inner edge with a downwardly extending rim

a^3 . When such rim is used, it will be slotted coincidently with the notches a^2 of the collar a . The tube G fits snugly within the inner edge of the collar a and against the rim a^3 . At the upper end it has an outwardly extending flange g which preferably is inclined upwardly toward the outer edge. At the outer edge it has a downwardly extending rim g' . The cylindric portion a' of the reservoir is 10 provided with an annular shoulder a^4 . The portion of the smaller diameter above the shoulder is surrounded by the rim g' of the tube G , and the lower edge of this rim rests upon the shoulder. In this way the tube G 15 is supported in such manner as to be free to rotate and yet is held with great stability.

The enlarged part d' of the outer shell D^2 of the wick tube extends over the flange g of the tube G and its downwardly extending 20 rim like portion surrounds the rim g' of said tube G . The rim g' rests on the shoulder a^4 and so does the part d' . The rim g' of the tube G has radially extending T-shaped projections g^2 on its outer surface. Preferably 25 these will be struck up out of the metal forming the rim and will be T-shaped. The downwardly extending portion of the part d' of the shell D^2 has a bearing upon these projections g^2 which permits of its rotation. The 30 downwardly extending portion of the part d' of the shell D^2 has a number of radial projections d^5 extending from its inner side and at such elevation that when the shell D^2 is lowered to its position upon the tube G and 35 partly rotated, these projections d^5 will slip under the cross pieces of the T-shaped projections g^2 on the tube G .

Preferably the flange g of the tube G will have upwardly extending projections g^3 extending from it and these may with advantage be struck up out of the metal forming the flange. They afford a bearing for the outwardly extending flange-like portion of the part d' of the shell D^2 . Preferably the flange-like portion of the part d' will be provided with perforations d^6 near its inner circumference to return any oil, and it will be advantageous to extend the shell D^2 below the flange-like portion of this part d' so as to form a 40 sort of petticoat d^{10} . The petticoat d^{10} fits snugly within the tube G and will therefore tend to preclude oil from passing out of the reservoir between the shell D^2 and the tube G . The outer shell of the wick tube above 45 the part d' will preferably be provided with perforations d^7 to afford a vent for gas.

It will be obvious from the foregoing description that if the outer shell D^2 of the wick tube is rotated after its engagement with the 50 tube G , it will impart a rotary motion to the latter.

I designates an outer air distributer constructed mainly of cylindric form, but having at the base an outwardly extending flange-like portion i and below this a downwardly extending rim-like portion i' . The latter surrounds the rim-like portion of the part d' of

the shell D^2 and has near the lower edge recesses i^2 which are of a size and are arranged in such positions that they may slip over the 70 lower portions of the projections d^4 of the shell D^2 and interlock therewith. The rim like portion i' is larger in circumference than the rim like portion of the part d' so that there is an air space between them and the 75 portions of the projections d^4 above the shoulder serve to center the distributor.

An outer air distributer J surmounts the air distributer I and the latter is provided with spring fingers I' for holding a chimney. 80

The reservoir may be filled through a well A^{10} provided with a removable stopper a^{10} . I have shown the lamp as provided with two deflectors or spreaders $K' K^2$ supported upon a post K which is sustained by spiders k in 85 the inner shell D' of the wick tube. This post will preferably be surrounded by a perforated cylinder L within the inner shell of the wick tube. The post K is made in two sections, one of which is provided with a 90 socket to enable it to fit over the other. The upper section has the deflectors $K' K^2$ fastened to it. These deflectors may be similarly constructed. Each will consist preferably of a sheet of mica protected against 95 splitting by pairs of clamping pieces $k' k^2$. Each clamping piece consists of a disk of sheet metal having parallel slits made in it at one point from the circumference to the central portion and having the strip of metal which 100 is intermediate of the slits bent transversely to the main portion of the disk. A hole is formed in the mica, the strips of metal bent from the disks are passed through the hole, the disks are pressed tightly against the mica 105 and then the said strips of metal are bent in reverse directions so that the strip of metal from each disk will embrace the other disk.

Another feature in the construction of the deflectors $K' K^2$ consists in forming a central 110 hole in the sheet of mica forming each deflector and in fitting to the post K above and below the sheet of mica a collar having a hub-like portion k^3 and a flange-like portion k^4 . The two collars $k^3 k^4$ will hold and protect the inner edge of the sheet of mica. These collars will be driven onto the post 115 friction tight.

What I claim as my invention, and desire to secure by Letters Patent, is—

1. In a lamp, the combination of a reservoir, a central draft tube, a wick carrier surrounding the same and provided with outwardly extending arms or pins, a spirally grooved or slotted tube receiving said arms or pins and 125 guides fastened in the reservoir and consisting of rods or wires, independent of and outside the wick tube substantially as specified.

2. In a lamp, the combination of a reservoir, a central draft tube, a wick carrier surrounding the same and provided with outwardly extending arms or pins, a spirally grooved or slotted tube receiving said arms or pins, guides 130 consisting of rods or wires fastened at the

lower ends to the bottom of the reservoir and an inwardly extending flange in the upper part of the reservoir having radial notches and having the upper ends of the rods or wires fastened to it adjacent to the notches, substantially as specified.

3. In a lamp, the combination of a reservoir, an annular wick tube shell, a wick carrier surrounding the same within the reservoir, a spirally grooved or slotted tube extending down into the reservoir and having at the upper end a flange which extends over the upper portion of the reservoir and an outer wick tube shell having a flange-like portion extending over the flange of the said tube, substantially as specified.

4. In a lamp, the combination of a reservoir, an annular wick tube shell, a wick carrier surrounding the same within the reservoir, a spirally grooved or slotted tube extending into the reservoir and having at the upper end a flange which extends over the upper portion of the reservoir, an outer wick tube shell having a flange-like portion extending over the flange of the said tube and a petticoat extending down within said tube, substantially as specified.

5. In a lamp, the combination of a reservoir, an inner wick tube shell in the reservoir, a wick carrier surrounding said inner shell, a spirally grooved or slotted tube for operating the wick carrier, a flange-like portion g on the

latter, a rim-like portion g' extending from said flange-like portion, projections g^2 on the rim-like portion, and an outer wick tube shell 35 having a downwardly extending rim-like portion provided with projections d^3 for centering and locking the said outer wick tube shell with respect to said tube, substantially as specified.

6. In a lamp, the combination of the outer wick tube shell D^2 having a portion provided with shouldered projections d^4 and the air distributor I having recesses for interlocking with said projections, substantially as specified. 40

7. A deflector for the burner of a lamp consisting of a sheet of mica having holes and fitted with clamping pieces passing through the holes, substantially as specified. 50

8. A deflector for the burner of a lamp, consisting of a sheet of mica having holes and consisting of disks provided with strips or tongues which may be passed through the holes and bent over at the extremities to 55 fasten the disks in place, substantially as specified.

In testimony whereof I have signed my name to this specification in the presence of two subscribing witnesses.
